7 Claims. (Cl. 35—46)

This invention relates to improvements in a terrestrial globe and more particularly to an improved mounting therefor.

Various types of mountings are known in the prior art for terrestrial globes. Examples of the conventional types of mountings include rotatable mounting on an inclined spindle, a semi-meridian ring mounting, a full meridian ring mounting, and a polar view mounting wherein the globe ball is supported in an arcuate cradle but is unattached and freely removable from the cradle. All of these various types of mountings have certain advantages for educational and other purposes. However, prior to the present invention globes have not been available which offer in a single structural unit the combined advantages and operating characteristics of these several different mounting arrangements.

Accordingly, one object of the invention is to provide a novel combination mounting for a terrestrial globe which permits the globe to be used in a plurality of different ways.

A further object of the invention is to provide a novel mounting means for a terrestrial globe which affords the combined features of both a meridian ring mounting and a polar view mounting.

An additional object of the invention is to provide an improved globe mounting means as described above which is characterized by a novel detachable relationship between the globe ball and its supporting structure.

Other objects and advantages of the invention will become apparent from the subsequent detailed description taken in conjunction with the accompanying drawings, wherein:

Fig. 1 is a side elevational view of a globe comprising one specific embodiment of the invention;

Fig. 2 is a side elevational view taken at 90° relative to the view seen in Fig. 1 and showing the parts of the globe in a different operating relation;

Fig. 3 is an enlarged fragmentary sectional view taken along the line 3—3 of Fig. 2;

Fig. 4 is a view similar to Fig. 1 but showing a modified form of the invention;

Fig. 5 is an elevational view taken at 90° relative to the view shown in Fig. 4 and with the parts of the globe disposed in a different operating relation; and

Fig. 6 is an enlarged fragmentary elevational view showing a structural detail of the invention.

Briefly described, our invention comprises a globe ball supporting structure which provides all of the characteristics and advantages of a swinging full meridian ring mounting and a polar view mounting. This objective is achieved by means of a cradle base adapted to receive the globe ball in freely turnable relation and a meridian ring swingably supported above the cradle base by means of a pair of upright diametrically opposed supports. As will hereinafter appear in detail, the globe ball is provided with a simple detachable rotatable connection between each of its poles and the meridian ring so that when the ball is rotatably mounted in the ring the globe

2

can be used in the conventional manner of a swinging full meridian ring mounted globe. However, when the ball is detached from the meridian ring it is supported by the cradle base for free turning movement in any direction or complete removal from the base for closer examination by the user. An important feature of the invention resides in the provision of a great circle scale along the meridian ring and the proper dimensional relationships such that when the globe ball is detached from the ring and supported on the cradle base the ring may be utilized to provide accurate great circle measurements on the surface of the globe ball.

Referring first to Figs. 1 to 3, one embodiment of the invention is shown comprising a globe ball 11, a base 12, and a meridian ring in the form of a flat circular band 13. The base 12 is formed in this instance from a pair of wood base members 14 and 16 which are secured to each other at right angles in the form of a cross. The lower edges of the members 14 and 16 are flat for supporting the device on a surface and the upper edges of the members 14 and 16 are formed with a curvature which conforms to the curvature of the globe ball 11. These upper curved edges of the members 14—16 are provided with a cushion or lining 17, such as felt or the like, so as to insure a smooth, non-scratching cradle support for the globe ball 11.

A pair of generally upright supporting arms 18 are rigidly attached, as by screws 19, at their lower ends to the base member 16 so that the upper end portions of the arms 18 are disposed in diametrically spaced relation at opposite sides of the meridian ring 13. The meridian ring 13 is in the form of a flat circular band having a width designated at B in Fig. 1. The ring or band 13 is provided with external indicia 21 constituting a great circle meter or scale which, in this instance, is readable at the lower edge of the band 13 as seen in Fig. 1. The band 13 is swingably supported in slightly spaced relation above the cradle surface 17 by means of pivot pins or rivets 22 extending between the upper ends of the arms 18 and the center of the width of the band 13. Friction collars or spacers 23 are interposed between the arms 18 and the band 13 to provide a limited frictional resistance so that the band 13 will be retained in any position to which it is moved. It will be appreciated that thumb screws or other means could be used in place of the friction joint 22—23 for providing the desired tight swingable mounting of the ring 13 on the arms 18.

The globe ball 11 has a detachable mounting within the meridian ring or band 13 so that the ball can be used in either of the two mounting positions heretofore mentioned. In the illustrated embodiment the detachable connection between the globe ball and the meridian ring is provided by means of a pair of spring pressed depressable plunger type pivot pins located at the poles of the globe and retaining the globe ball 11 at the proper axial inclination relative to the ring 13, as seen in Fig. 2. The pivot means at each pole of the globe ball 11 is designated generally at 24 and is best seen in Fig. 3. Thus, the pivot means 24 comprises an elongated tubular element 26 having a detachable sliding fit through a grommet 27 which is seated in an axial opening in the shell of the globe ball 11 for rotatably mounting the usual time disk 28. The outer end of the tubular element 26 is flanged, as at 29, and seats against the grommet 27. A plunger 31 is slidably fitted in the tubular element 26 and has an outermost reduced diameter end portion or pin 32 which projects through an opening 33 into the band 13. A guide stem in the form of an elongated screw 34 is threadedly connected to the inner end of the plunger 31 and has a head portion 36 which contacts with a complementary countersunk aperture in the

lower end of the tubular element 26. A spring 37 encircles the stem 34 and coacts between the inner end of the tubular element 26 and the inner end of the plunger 31 for normally urging the latter outwardly, the screw head 36 serving to limit the extent of outward movement of the plunger 31. In the position shown in Figs. 2 and 3, the globe ball 11 is journaled in the meridian ring 13 by means of the plunger pins 31-32 and the globe can then be used in the usual manner of a swinging full meridian ring mounted globe. Because of the slight spacing between the meridian ring 13 and the cradle surface 17 it will be understood that the ring 13 is swingable through 360° so that all parts of the globe surface are easily visible.

By manual depression of the plunger pins 31-32 or slight distortion of the band 13, it will be seen that the pin portions 32 can readily be disengaged from the ring openings 33 so that the globe ball 11 can be completely detached from the meridian ring 13. The globe ball 11 is then supported in freely turnable relation on the cradle surface 17 as seen in full lines in Fig. 1. To facilitate free turning movement of the globe ball 11, the pivot assemblies 24 are each removable as a unit from the globe ball 11 by reason of the slideable fit of the tubular element 26 in the grommet 27. After removal of the pivots 24 they may be conveniently stored in a pair of bores 38 provided in the opposite ends of the base member 14. Although the pivot assemblies 24 comprise a convenient method of detachably connecting the globe ball 11 to the meridian ring 13, it should be understood that other removable pivotal connections can also be used such as thumb screws, threaded knobs, or the like.

Referring now to Fig. 1, an important advantage of the invention is found in the provision of the great circle scale 21 which is disposed at the lower edge of the band 13 when the latter is in horizontal position as shown in Fig. 1. However, in order to obtain accurate great circle measurements between any two points on the surface of the globe ball 11 when the latter is supported in the cradle 17, it is necessary that the spherical center of the globe ball 11 be aligned in the plane of the lower edge of the band 13. Consequently, in the illustrated embodiment, when the globe ball 11 is supported by means of the pivots 24, the ball is positioned so that its spherical center falls in a plane passing through the exact center of the width of the band 13, and furthermore the pivot pins 22 swingably mount the band 13 at the center of its width. By dimensioning the upright support arms 18 such that the meridian ring mounted globe ball 11 is suspended a predetermined distance A above the cradle surface 17 which is equal to exactly one-half the width B of the band 13, it will be seen that when the ball 11 is detached from the ring 13 and allowed to rest on the cradle surface 17 its spherical center will be lowered by the distance A so that the globe ball center is then aligned in the plane of the lower edge of the band 13. In Fig. 1 the uppermost ring mounted position of the globe ball 11 is indicated in broken lines and the cradle supported position is indicated in full lines. When the ball is in the latter position, by positioning the meridian ring 13 in horizontal position, as in Fig. 1, it will be seen that it is a simple matter to rotate the ball 11 with respect to the cradle surface 17 in order to align any two spaced points with the great circle scale 21 and thereby obtain a reading of time differences, mileage, or degrees of latitude and longitude.

In Figs. 4 to 6, a modified form of the invention is shown which possesses some advantages in that it permits a greater degree of clearance between the swingable meridian ring and the base and also permits reading of the great circle scale at the upper edge of the meridian ring instead of the lower edge. In Figs. 4 to 6 the parts of the structure which are identical with the previous embodiment have been identified by the same reference

numerals. Thus, the globe ball 11 is detachably mounted by pivot assemblies 24 in the meridian ring 13 which is in turn supported from the arms 18 extending upwardly from the base 12 having a cushioned cradle surface 17. However, in this instance the indicia, designated at 41, comprising the great circle scale are arranged to be read at the upper edge of the band 13 when the latter is in horizontal position as seen in Fig. 4. Furthermore, the swingable mounting of the band 13 on the arms 18 is different from the previously described embodiment. In the previous embodiment the ring 13 was swingably mounted on a fixed horizontal axis. In the present embodiment the ring 13 is arranged so as to be swingably positioned on either of two upper and lower horizontal axes. Thus, the upper end portions of the support arms 18 are formed with inverted generally L-shaped slots 42 each having an upper end portion 43 defining upper journals for the upper horizontal axis position of the ring 13 and a lower end portion 44 defining lower journals for the lowermost horizontal axis position of the ring 13. A pair of studs or pins 46 project rigidly in diametrically opposed relation from the band 13 and extend through the slots 42 in the arms 18. Friction collars or spacers 23 are provided as before, and wing nuts 47 are threadedly mounted on the outer ends of the studs 46 for providing the desired tight but swingable mounting of the meridian ring 13.

In Fig. 5 the globe is shown in meridian ring mounted position as supported by the pivots 24 in the ring 13. The meridian ring 13 is journaled on its uppermost horizontal axis with the pivot pins 46 disposed in the upper journals 43 of the slots 42 so that the ring 13 is in elevated freely swingable relation above the cradle surface 17. In Fig. 4 the globe ball 11 is shown in full lines in cradle supported position after detachment from the ring 13. In order to provide accurate great circle measurements, it will be seen that the ring 13 is oriented in horizontal position and has been shifted so that the pins 46 are supported in the lowermost journals 44 of the slots 42 so that the meridian ring is supported on its lower horizontal axis. In this position the spherical center of the globe ball 11 is aligned in the plane of the upper edge of the band 13 so that the great circle scale 41 provides the desired accurate great circle measurements. By proper dimensioning of the support arms 18 and the slots 42 it will be understood that the spherical center of the globe is lowered a distance A, which is equal to the width B of the band 13 when the globe ball is moved from its broken line position to its full line position as seen in Fig. 4. Of course, it will be understood that the band 13 is swingably supported at the center of its width B and that the globe ball 11, when supported by the pivots 24, is likewise supported with its spherical center aligned in the plane of the center of the band 13. It will also be understood that by manipulation of the wing nuts 47 the meridian ring 13 is easily shiftable between the communicating upper and lower portions of the slots 42.

Although it is possible in the Figs. 4 to 6 embodiment to arrange the relative dimensions of the parts so that the great circle scale can be located at the lower edge of the meridian ring 13, the advantage of the present embodiment resides in the fact that it permits a greater tolerance or clearance between the ring 13 and the cradle surface 17 when the globe is in meridian ring mounted relation, and to obtain this added tolerance it is desirable to have the scale 41 at the upper edge of the ring 13. As will also be evident, it is frequently easier to read the scale at the upper edge of the ring 13. It should also be pointed out that the longer leg of each slot 42 is disposed at a slight angle so as to minimize the extent of lateral displacement of the band 13 relative to the globe ball 11 when the latter is in its cradle supported position.

Although the invention has been described with particular reference to certain specific structural embodi-

ments thereof, it is to be understood that various modifications and equivalents may be resorted to without departing from the scope of the invention as defined in the appended claims.

We claim:

1. In a terrestrial globe, the combination of a globe ball, a base having a cradle surface for receiving the ball in freely rotatable relation, a meridian ring comprising a circular band having said ball rotatably and detachably journaled at its poles in said band, said band bearing external indicia providing a great circle scale at one circumferential edge thereof, and a pair of supports extending upwardly from said base in diametrically spaced relation and having said band swingably connected thereto for supporting said ball at a predetermined distance above the cradle surface of said base when said ball is journaled in said band, said distance being such that when the ball is detached from said band and supported on said cradle surface, the spherical center of the ball is aligned in the plane of said one edge of the band for providing accurate great circle measurements on the surface of said ball.

2. The structure of claim 1 further characterized in that said ball is journaled in said band by means of a pair of pivot members extending axially through a pair of apertures in said band and receivable in axial recesses at the poles of said ball, said pivot members being removable from the band and from the ball for disconnecting the ball from said band.

3. In a terrestrial globe, the combination of a globe ball, a base having a cradle surface for receiving the ball in freely rotatable relation, a meridian ring comprising a flat circular band having said ball journaled at its poles therein and removable therefrom, and a pair of supports extending upwardly from said base in diametrically spaced relation and having said band swingably connected thereto on a fixed horizontal axis for supporting said ball a predetermined distance above the cradle surface of said base when said ball is journaled in said band, said band being provided with external indicia comprising a great circle scale at the lower circumferential edge of the band when the latter is in horizontal position, and said distance being such that when said ball is detached from the band and supported on said cradle surface, the spherical center of the ball is aligned in the plane of said lower edge of said band for providing ac-

curate great circle measurements on the surface of said ball.

4. The structure of claim 3 further characterized in that said band is connected to said supports at the center of the width of the band and said distance is equal to one-half the width of the band.

5. In a terrestrial globe, the combination of a globe ball, a base having a cradle surface for receiving the ball in freely rotatable relation, a meridian ring comprising a flat circular band having said ball journaled at its poles therein and removable therefrom, a pair of meridian ring supports extending upwardly from said base in diametrically spaced relation, and means for swingably connecting said band to said supports on either of a pair of upper and lower horizontal axes, said ball being supported a predetermined distance above the cradle surface of said base when said ball is journaled in said band and said band is swingably mounted on said supports on said upper horizontal axis, and said band being provided with external indicia comprising a great circle scale at one circumferential edge thereof and the spherical center of said ball being aligned in the plane of said one edge when the band is swingably mounted on said lower horizontal axis with the ball detached from the band and supported on said cradle surface.

6. The structure of claim 5 further characterized in that said band is connected to said supports at the center of the width of the band in both upper and lower positions thereof, said great circle scale is at the upper edge of the band when the latter is in horizontal position, and said distance is equal to the width of the band.

7. The structure of claim 5 further characterized in that said supports are formed with inverted generally L-shaped slot means providing spaced upper and lower journals for a pair of pivot members extending between the band and said slot means.
